CHARLES E. MISER, OF WATERTOWN, NEW YORK.

EXPANSIBLE AND CONTRACTILE CORE FOR PAPER AND SIMILAR ROLLS.

1,135,388.

Specification of Letters Patent. Patented Apr. 13, 1915.

Application filed January 30, 1914. Serial No. 815,416.

To all whom it may concern:

Be it known that I, CHARLES E. MISER, of Watertown, in the county of Jefferson, in the State of New York, have invented new 5 and useful Improvements in Expansible and Contractile Cores for Paper and Similar Rolls, of which the following, taken in connection with the accompanying drawings, is a full, clear, and exact description.

10 This invention relates to certain improvements in expansible and contractile cores for paper and similar rolls involving the use of a plurality of cylindrical segments arranged about the axis of a central shaft 15 carrying cams coöperating with suitable bearings on the segments for forcibly expanding the core radially within the paper roll to frictionally lock said core to the roll so that the paper may be readily reeled 20 thereon and therefrom.

The main object is to standardize this class of cores so that duplicates may be supplied to the manufacturers and purchasers of the paper rolls for repeated use, thereby obviating the necessity of carrying a large 25 stock of cores and also of re-transportation from purchasers to manufacturer and visa versa.

Another important object is to simplify 30 the general structure of the core by reducing the number of parts and cost of manufacture and at the same time to increase its gripping and releasing efficiency in and from the roll of paper or other material 35 carried thereby.

One of the specific objects is to make the periphery of the segments cylindrical and of uniform area and to oppositely guide said segments in radial lines during the 40 operation of expanding or contracting the core so as to produce a maximum frictional contact between the segments and roll concentric at all points with the axis of the operating shaft or spindle.

45 Another object is to provide simple means accessible at the ends of the core for positively locking the segments in their radially extended positions so as to relieve in a measure the pressure of the segments upon 50 the expanding cams which might tend to shift the cam and loosen the core in the roll.

A still further object is to provide simple means for preventing relative axial movement of the segments and operating 55 means including the shaft and cams.

Other objects and uses will be brought out in the following description.

In the drawings—Figures 1 and 2 are respectively a side elevation and end view of an expansible core embodying the various 60 features of my invention. Figs. 3 and 4 are enlarged longitudinal sectional views of the same core taken on line 3—4, Fig. 2, except that the core is shown as expanded in Fig. 3 and as contracted in Fig. 4. Figs. 5 and 6 are 65 enlarged cross sectional views taken on line 5—6, Fig. 1, except that, in Fig. 5, the core is expanded and, in Fig. 6, it is contracted. Fig. 7 is an enlarged sectional view taken on line 7—7, Fig. 1. Fig. 8 is a detail sectional view of the central portion of the core showing a modified means of holding the adjacent portions of the segments against sagging.

As illustrated this core comprises a plurality of, in this instance three, cylindrical segments —1— of uniform size, arranged in parallelism uniform distances apart around the axis of a shaft or spindle —2—, each segment being provided intermediate its 80 ends with a plurality of, in this instance, three internal cam bearings —3—, which are engaged by the cam teeth of a corresponding number of cam collars —4—, the latter being rigidly secured by set screws 85 —5— or keys —6— or both to the shaft or spindle —2— to rotate therewith.

These cores may be of any desired length according to the width of the paper or other material carried thereby, the shaft —2— 90 being centrally located therein and extended some distance beyond the ends of the segments so that the ends thereof are provided with journals adapted to be supported in suitable bearings at the ends of the segments 95 for conveniently supporting the roll while the paper is being wound thereupon or therefrom, one end, as —7—, of the shaft being angular or square in cross section for the reception of a crank or wheel or other operating means by which the shaft may be rotated relatively to the other segments in the operation of expanding or contracting the core in a manner presently described.

The segments —1— are continuous from 105 end to end and parallel with the axis of the shaft and their peripheries are circular in cross section and of a radius equal approximately to the maximum degree of expansion so as to afford a maximum gripping fric-

tional contact area with the interior of the paper roll at all points throughout their surfaces, thereby forming a circular opening through the center of the rolls which permits the core to be more easily inserted into and withdrawn from said roll.

The cam bearings —3— are secured by rivets —3'— or other suitable fastening means to the inner faces of their segments —1— and are spaced uniform distances apart, the outermost bearings being located some distance inwardly from the ends of the segments to permit the use of special forms of locking and guiding devices hereinafter described, each bearing being provided at its ends with inwardly projecting radial flanges —8— of uniform radial depth adapted to engage opposite ends of their respective cam collars —4— to keep the cams in registration with the bearings and also to assist in holding the segments —1— and their expanding means, such as the shaft —2— and cam collars —4—, against relative endwise movement. The opposite ends of the segments —1— are provided with internal guide members —9— rigidly secured thereto by rivets —10— or equivalent fastening means, each guide member —9— being provided with an inwardly projecting axially extending lock-stop —11— spaced some distance apart from the inner face of the segment —1— for co-operative engagement with a guide ring —12— and shaft —2—, to limit radial movement of the segments —1— and also to co-operate with a locking collar —13— on the shaft to hold the segments in their expanded relation.

The sleeves —12— are loosely mounted on opposite ends of the shaft within the corresponding ends of the segments —1— so that the shaft may be turned therein, but are held against endwise or axial movement between the inner ends of the guide members —9— and stop collars —14—, which latter are held in their adjusted positions by set screws —15— to the shaft —2— and assist in holding the segments —1— and shaft —2— against relative endwise movement through the interposition of the sleeves —12— between the collars —14— and guide members —9—.

The guide members —9— are slidably interlocked with the sleeves —12— through the medium of guide ribs —17— which are slidably fitted in recesses or grooves —16— in the adjacent ends of the guide members —9—.

The space between the stops —11— and outer annular flanges of the adjacent rings —12— is sufficient to allow the desired radial movement of the segments —1— corresponding approximately to the throw of the cam teeth of the cam collars —4—. I have shown each cam collar as provided with a plurality of, in this instance three,

cam teeth —4'— spaced uniform distances apart circumferentially and terminating in abrupt end faces adapted to normally contact with the adjacent flat sides of the ribs or bearings —3— when the segments of the core are contracted as shown more clearly in Fig. 4 in which case the ends of the segments abut against each other. These cam collars —4—, which are secured to the shaft —2—, constitute the means for expanding the core by forcing the segments —1— radially and outwardly uniform distances by reason of the fact that the cams are all of the same throw, it being understood that when the segments are released by the return of the cams to their normal positions, the pressure of the paper upon the segments will tend to force them inwardly aided by their own weight which causes them to move to the limit of their inward movement when elevated above the horizontal plane of the axis of the shaft, the relief from pressure or frictional contact with the paper being sufficient to permit the entire core to be withdrawn when desired.

The means for locking the segments in their extended positions consist of the collar —13— which is slidable axially upon the shaft into and out of position between the flange —11— and periphery of the shaft, the combined thickness of the collar —13— and stop —11— being substantially equal to the radial distance between the periphery of the shaft and inner face of the annular flange of the ring —12— so that when the collar —13— is adjusted to its locking position, it firmly holds the segments against inward movement, thereby relieving in a measure the pressure of the segments upon the faces of the cams —4'—, it being understood that the collars —13— may be held in their locking positions by suitable means as set screws —18—. On the other hand when it is desired to release and withdraw the core, it is simply necessary to loosen the set screws —18— and withdraw the collars —13— from within the flanges —11— and then to rotate the shaft —2— until the low points of the cams —4'— are registered with their respective bearings —3—, whereupon the segments will be released from engagement with the paper and permit the entire core to be withdrawn or reinserted at will.

Suitable means is provided for preventing the sagging of the central portions of the core-segments under their own weight away from the shaft —2— particularly when the cores are of considerable length, and for this purpose the cam bearings —3— at or near the center of the core are provided with axially projecting flanges —8— fitting within an annular flange —20— of a collar —21— which is loosely mounted on the shaft —2— to allow the latter to turn

therein and is held against outward end-
wise movement by a stop screw —22— as
shown in Fig. 3 or by a separate collar
—23— as shown in Fig. 8, the latter being
5 held in place by a set screw —24—.

What I claim is:

1. An expansible and contractile core for paper and similar rolls comprising a shaft, radially movable segments of a cylinder surrounding the shaft and having inwardly projecting members, means actuated by the turning of the shaft for operating said segments, and collars slidable on the shaft across the inner ends of said members for 10 holding the segments in their expanded relation irrespective of the cams.
2. An expansible and contractile core for paper and similar rolls, comprising a shaft, cams tight on the shaft, radially movable segments of a cylinder surrounding the shaft and provided with bearings resting on the cams, guide rings loosely mounted on the shaft independently of the cams, but adjacent thereto, coöperative guide members on 15 the segments and rings, respectively, for guiding the segments in their radial movement and holding them in concentric relation to the axis of the shaft, and coöperative stops on the guide members on the segments 20 and rings, respectively, for limiting the outward movement of the segments.
3. An expansible and contractile core for paper and similar rolls, comprising a shaft, cams tight on the shaft, radially movable segments of a cylinder surrounding the shaft and provided with bearings resting on 25

the shaft independently of the cams, but adjacent thereto, coöperative guide members on the segments and rings, respectively, for 40 guiding the segments in their radial movement and holding them in concentric relation to the axis of the shaft, coöperative stops on the guide members on the segments and rings, respectively, for limiting the outward movement of the segments, and locking collars slidable on the shaft across the inner ends of the guide members on the segments for holding said segments in their 45 expanded relation. 50

4. An expansible and contractile core for paper and similar rolls comprising a shaft, a plurality of segments of a cylinder of uniform size arranged about the axis of the shaft, cam bearings on the inner faces of 55 the segments, cams secured to the shafts and engaging said bearings for moving the segments radially as the shaft is rotated relatively to the segments, guide flanges for keeping the cams and bearings in registration, stop collars adjustably secured to the shaft near the ends of the segments, rings abutting against said collars, radially sliding interlocking connections between the segments and sleeves, and means for locking 60 the segments in their outermost positions. 65

In witness whereof I have hereunto set
my hand this 23rd day of January, 1914.

CHARLES E. MISER.
